2,548,891

METHOD OF MAKING A SHAVING AID

Emil Gantner, Zurich, Switzerland

No Drawing. Application November 4, 1947, Serial No. 784,082. In Switzerland November 14, 1946

1 Claim. (Cl. 167—92)

1

This invention relates to a method of making a shaving aid and also to a shaving aid made in accordance with this method.

Talc powder and similar substances for promoting sliding make shaving easier, particularly shaving by means of electric dry-shaving apparatus, since this powder removes sweat from the skin and thereby increases the ease of sliding. Talc or similar powders are however impractical in service, since their use entails an undesirable formation of dust.

The hitherto known methods of shaping talc, i. e. of pressing it into bars or blocks, are unsatisfactory since they all possess the drawback of giving off too much talc powder when used and of greatly dirtying the clothes in consequence of the poor adherence of the talc powder to the skin and the hairs of the beard.

The present invention endeavours to remove this drawback.

According to the method in this invention at least one fatty substance, solid at ordinary ambient temperature, is melted and intimately mixed with a substance to promote sliding, for instance talc powder, which is heated to at least the melting temperature of the fatty substance; the mixture is then pressed into shaped pieces.

The shaving aid obtained in accordance with this method consists of a shaped piece which contains at least one substance to promote sliding, intimately mixed and physically combined with fat.

The mixture is homogeneous and contains for instance, up to 20% by weight of fat of mineral, vegetable, animal or chemical origin, with respect to the weight of the sliding-promoting substance, for instance talc or a neutral soap.

To the mixture, one or more antiseptics, colouring matters, and scents may be added.

A particularly suitable fat is, for instance, spermaceti. As means to promote sliding talc is preferably used, but other substances with similar physical properties could be also adopted.

As colouring matter ochre may be added and

2

as scent essence of eau de Cologne, for instance. Antiseptics, one or several of which may be mixed in, are for instance phenol, kresol, phenyl salicylate (salol).

5 Talc or a similar sliding-promoting substance, heated to over the melting temperature of the one or more fatty substances and added to them, gives a homogeneous mixture.

The fat may also be a mixture of several kinds of fat.

I claim as my invention:

A method of making a shaving aid for use with electric razors, which comprises melting a quantity of spermaceti wax, preheating at least 15 five times that amount by weight of talcum powder to a temperature substantially equal to that of the molten wax, and adding the pre-heated talc to the molten wax under agitation until a homogenous mixture is formed, and 20 pressing said mixture into shaped pieces.
